EASEL CONSTRUCTION

Howard M. Fancher, Rochester, N. Y., assignor to
The Rochester Folding Box Co., Rochester,
N. Y., a corporation of New York

Application June 23, 1934, Serial No. 732,133

12 Claims. (Cl. 248—198)

This invention relates to an easel such as is used by artists, illustrators, and the like, and by children who wish to draw.

An object of the invention is to provide a simple, compact easel of few parts, easy and inexpensive to construct, and light in weight so that it may be readily transported from place to place.

Another object is the provision of such an easel 10 so designed and constructed that it may be readily collapsed and set up.

To these and other ends the invention resides in certain improvements and combinations of parts, all as will be hereinafter more fully described, the novel features being pointed out in the claims at the end of the specification.

In the drawing:

Fig. 1 is a perspective view of an easel constructed in accordance with a preferred embodiment of the invention;

Fig. 2 is a front view of the same in erected position;

Fig. 3 is a plan thereof, and

Fig. 4 is a fragmentary vertical section taken 25 substantially on the line 4—4 of Fig. 3.

The same reference numerals throughout the several views indicate the same parts.

The easel in its preferred form comprises a piece of suitable sheet material provided with two 30 vertical scores 11 forming weakened lines for hinge joints so that the sheet material is subdivided into a central portion or panel 12 and two wing portions or panels 13 which may be bent at an angle to the central portion 12, as shown, 35 so that the sheet may stand upright on any suitable flat surface such as the floor.

Attached to the central panel 12 is an easel portion preferably constructed of a single piece or strip of suitable sheet material starting, for 40 example, at an edge 15, thence extending upwardly at 16 to a score line 17, at which it is bent to extend downwardly at 18 to another score line 19. From the score line 19 the strip extends obliquely rearwardly at 20 to the panel 12, where 45 it is again bent at 21 extending downwardly a short distance to the score line 22 and thence outwardly again at 23 substantially parallel to the portion 20. The portion 23 is somewhat longer than the portion 20 and projects outwardly materially beyond the score line 19, as shown in Fig. 4, where it is scored at 24, extends upwardly a short distance at 25, is again scored at 26, then extends rearwardly at 27 and is doubled back upon itself at 28 to pass forwardly once 50 more at 29 to its final terminal edge 30. The strip

thus scored and folded is held in proper position by suitable fastening means such as the bolts 35 passing through the portion 16 of the easel strip and through the panel 12, and the bolts 36 passing through the easel strip between the score lines 21 and 22 and through the panel 12, and the bolts 37 passing through the portions 20, 23, 27, and 29 of the strip. It can be readily seen from Fig. 4 that when fastened in this manner, the strip provides a rigid and effective construction in which the upper surface of the portion 27 10 forms a suitable shelf on which the lower edge of a pad or sheet of paper may rest, and the portion 18 provides an inclined backing portion against which the sheet or pad may lie while it is being drawn or painted upon. The portions 20, 23, 27, and 29 may be collectively called a base portion, since they form a base for holding the lower edge of the backing portion 18 in proper position.

Preferably the shelf provided by the parts 21 and 29 is sufficiently wide so that various drawing or painting supplies may be placed on this shelf in addition to the pad or sheet of paper which stands upon it. For example, a suitable 25 box or container 40 may be either loosely placed on or securely fastened to the shelf, for holding crayons, paints, or any other suitable supplies. If the box 40 is fastened to the shelf, a space is 30 preferably left between the box and the inclined surface 18, as shown in Fig. 4, so that the bottom edge of a pad or sheet of paper may enter this space, and the container 40 forms an abutment preventing the bottom of the paper from accidentally sliding forwardly off of the shelf.

Both the panels 12 and 13, and also the strip 18, 20, 23, etc., are preferably made of fiber board, and it is found that excellent results are obtained by the use, for both of these sheets, of corrugated fiber board of the type in which both surfaces of the fiber board have smooth facing sheets over the corrugations. The sheet from which the panels 12 and 13 are made preferably has the corrugations extending vertically, so that they are parallel to the score lines 11.

If desired, any part of either of the sheets may be coated with a suitable compound to provide a chalk taking or blackboard surface. Also, any suitable decorations may be applied to any part of either of the sheets, as for example, the 45 decoration indicated diagrammatically by the panels 50 printed or painted on the sections 12 and 13.

An advantage of using fiber board is that pins, 50 nails, or the like can readily pierce the board at 55

any desired point. Thus, for example, a pin 52 may be placed wherever desired on one of the panels, to serve for holding any drawing implements such as the triangle 53 when not in use, 5 and a tablet or package of drawing paper 54 may be secured to one of the panels as by means of pins 55.

If desired, suitable means may be employed for holding the wing portions 13 in proper open 10 position. For example, a cross piece 60, made of a strip of fiber board, may extend through the space between the members 20 and 23 and have its ends 61 turned at an angle so as to lie along the surfaces of the wing walls 13 and be fastened 15 to them by bolts 62. Bolts 63 may also be employed to fasten the strip 60 to the members 20 and 23 if desired, though usually this is unnecessary.

Conjointly with the holding member 60, or as a substitute therefor, a holding or brace member 70 may be used, which acts also as a floor. 20 The ends 71 of the member 70 are turned up to lie against the inner or preferably the outer faces of the walls 13, and are secured thereto as by bolts 72. This member 70 steadies and 25 strengthens the whole structure, and has the further advantage of forming a protective bottom or floor for catching paint or other articles accidentally dropped by the person using the easel, so that the rug or other floor covering on 30 which the easel is placed will not be damaged.

Neither form of brace or holding member interferes with collapsing the easel, for the bolts may be removed or replaced in a moment. Both forms of holding member may be made of fiber 35 board of the same kind of which the panels 12 and 13 are made, or of any other suitable material.

The easel may obviously be made of various sizes to accommodate it either for children or adults, and it is seen that the construction is 40 extremely economical since all of the principal parts are made of fiber board. It is light and compact, and may be easily moved from place to place.

If it is desired to collapse the structure still 45 farther than can be done by turning the parts 12 and 13 into a common plane, then complete collapsing may be accomplished by removing the bolts 35, 36, and 37, the nuts of which are sufficiently loose so that they can be unscrewed simply 50 by the fingers without the use of any tools. When these bolts are removed, the strip forming the parts 18, 20, 23, etc., may be unfolded and refolded into a more compact flat shape.

While one embodiment of the invention has 55 been disclosed, it is to be understood that the inventive idea may be carried out in a number of ways. This application is therefore not to be limited to the precise details described, but is intended to cover all variations and modifications 60 thereof falling within the spirit of the invention or the scope of the appended claims.

I claim:

1. An easel comprising two sections of sheet material hingedly connected to each other and 65 adapted to be placed at an angle to each other to form a structure capable of standing upright on a supporting surface, and an inclined member secured to one of said sections to form a support for a sheet of paper, said inclined member being of less width than said section to which 70 it is secured and being supported wholly by said section independently of the other section.

2. An easel comprising two sections of sheet material hingedly connected to each other and 75 adapted to be placed at an angle to each other

to form a structure capable of standing upright on a supporting surface, a member attached near its upper edge to one of said sections and extending thence obliquely downwardly and outwardly to form an easel surface, and a member extending outwardly from said one of said sections to and beyond the lower edge of said first member to hold said lower edge and to form a shelf adjacent said lower edge. 5

3. The combination with a panel, of a piece of sheet material attached at one point to said panel and extending thence obliquely downwardly and outwardly away from said panel, thence inwardly to said panel, and thence again outwardly and projecting outwardly beyond said downwardly extending portion to provide a supporting shelf adjacent the bottom of said downwardly extending portion. 10

4. An easel comprising an upright member, and a strip of scored and folded sheet material secured to said upright member, said strip including a backing portion extending obliquely with its upper end relatively close to said upright member and its lower end spaced a substantial distance from said upright member, and a base portion extending from said upright member outwardly to the bottom of said backing portion and projecting beyond said bottom to provide a shelf. 15

5. A construction according to claim 4, further including detachable means connecting said backing portion to said upright member, and other detachable means connecting said base portion to said upright member. 20

6. An easel comprising a sheet of fiber board scored along two substantially vertical spaced 25 lines to provide three panels which may be bent at an angle to each other to form a structure capable of standing upright on a supporting surface, a second sheet of fiber board scored and folded to provide an oblique backing portion having its upper end relatively close to the central 30 one of said three panels and its lower end substantially spaced from said central panel, a base portion connected to said lower end and extending inwardly therefrom to said central panel, and a shelf portion extending outwardly from said lower end, and means connecting said second sheet of fiber board to said central panel of said first sheet of fiber board. 35

7. A construction according to claim 6, further 40 including a container secured to said shelf portion and spaced outwardly from said lower end of said backing portion. 45

8. An easel comprising a central section and two wing sections of sheet material hingedly connected to each other and adapted to be placed at an angle to each other to form a structure capable of standing upright on a supporting surface, an inclined member secured to said central section to form a support for a sheet of paper, said inclined member being of a width not greater than that of said central section and being supported from said central section independently of said wing sections, and a member extending between and secured to both of said wing sections to hold them in predetermined position relative to each other. 55

9. An easel comprising a central section and two wing sections of sheet material hingedly connected to each other and adapted to be placed at an angle to each other to form a structure capable of standing upright on a supporting surface, an inclined member secured to said central section to form a support for a sheet of paper, said inclined member being of a width not greater than that 60

of said central section and being supported from said central section independently of said wing sections, and a floor member secured adjacent opposite ends to said wing sections to hold them in predetermined position.

- 5 10. An easel comprising a central section and two wing sections of sheet material hingedly connected to each other and adapted to be placed at an angle to each other to form a structure capable of standing upright on a supporting surface, an inclined member secured to said central section to form a support for a sheet of paper, said inclined member being of a width not greater than that of said central section and being supported from said central section independently of said wing sections, and a member extending between said wing sections at approximately the elevation of the bottom of said inclined member and secured to both of said wing sections to hold them in predetermined position.
- 10 15. An easel comprising a central section and two wing sections of sheet material hingedly connected to each other and adapted to be placed at an angle to each other to form a structure capable of standing upright on a supporting surface, an inclined member secured to said central section to form a support for a sheet of paper, said inclined member being of a width not greater than that of said central section and being supported from said central section independently of said wing sections, and a floor member having upturned edges secured to said wing sections to hold them in predetermined position.

11. An easel comprising a central section and

two wing sections of sheet material hingedly connected to each other and adapted to be placed at an angle to each other to form a structure capable of standing upright on a supporting surface, an inclined member secured to said central section to form a support for a sheet of paper, said inclined member being of a width not greater than that of said central section and being supported from said central section independently of said wing sections, and a member extending between said wing sections at approximately the elevation of the bottom of said inclined member and secured to both of said wing sections to hold them in predetermined position.

12. A construction according to claim 6, further including a member extending between and secured to two of said panels to hold them in predetermined position.

HOWARD M. FANCHER.
